UNITED STATES PATENT OFFICE.

EDWARD T. CURRAN, OF DETROIT, MICHIGAN.

AIRPLANE-RADIATOR.

1,374,190.

Specification of Letters Patent. Patented Apr. 12, 1921.

Application filed October 19, 1918. Serial No. 258,815.

To all whom it may concern:

Be it known that I, EDWARD T. CURRAN, a citizen of the United States, residing at Detroit, county of Wayne, State of Michigan, have invented a certain new and useful Improvement in Airplane-Radiators, and declare the following to be a full, clear, and exact description of the same, such as will enable others skilled in the art to which it pertains to make and use the same, reference being had to the accompanying drawings, which form a part of this specification.

My invention relates to radiators adapted for use on airplanes and like devices.

Heretofore much difficulty has been experienced in keeping the radiators of airplanes from leaking. The sudden shock of descending and striking the earth is very apt to burst soldered joints, another weak point due to their ordinary construction. An object also is to save as much weight as possible in the construction of the radiator and still leave it efficient and sufficiently strong to resist the rough usage incident to such device. Another object of my invention is to provide a radiator for airplanes and means for more efficiently cooling the engine with the same weight and volume of liquid and also to obtain means for controlling the admission of air to the radiator making such means adjustable, a matter which is quite necessary owing to the sudden changes in temperature and velocities to which it is subjected. The advantages thereof and the nature of the invention will more fully appear in the following description and the claims.

In the drawings:

Figure 1 is the front of the radiator which has an opening for the purpose of permitting the propeller shaft to extend therethrough.

Fig. 2 is a vertical section of Fig. 1 on the line X—X with said features added which could only appear in Fig. 2.

Fig. 3 is a cross section of Fig. 1 on the line Y—Y.

Fig. 4 is a rear view of Fig. 1.

Fig. 5 is a view partly in section on the line Z—Z of Fig. 1 and showing an enlarged view of Fig. 2.

Fig. 6 is a cross sectional view of the vertical tubes which are shown in Fig. 3 and which appear in Fig. 2.

Fig. 7 is a view of the peculiar means for delivering cold air to the cylinders of the

V-shaped twelve-cylinder engine of the usual type.

In the drawings, similar letters refer to similar parts.

In Fig. 1 which represents the front of the radiator, A is the front shield. This front is curved as shown in Fig. 3. Perforations are made in this sheet, a large one at B in line with the crank shaft of the engine, not shown, and through which the propeller shaft, not shown, extends. The front piece A is double, as shown in Fig. 5 with a water space A² between them. These two plates are punched out and the edges brought down together leaving openings A³. These perforations extend over the whole face of the frontal sheets united as shown in Fig. 1 at A⁴, A⁵ by welding the edges of the perforations in the respective sheets when they are brought together. I am thus enabled to make a compound frontal section of the radiator with air passages which is shown in Fig. 1 as A⁶, A⁷. Inside or back of the air spaces of the shell thus formed in front is a damper A⁷ through which there are perforations, A⁸, and by raising or lowering this damper the full size of the perforations may be maintained or regulated at will which is done by a small crank A⁹ operated by a rod and handle A¹⁰ carried to any convenient point within reach of the operator. In rising or in high altitudes or rapidly descending when the air rapidly cools we can start with the full openings from the ground and gradually close them so as to prevent the too rapid chilling of the engine and its insufficient work caused thereby. Passing now to Fig. 3 in which A is the frontal shield, A¹ is the rear shield forming a curved water chamber, and since the section is taken on the solid lines Y—Y, the perforations in the shields do not appear. Back of this shield are placed vertical pipes B¹, B² of a peculiar shape, the cross section of which is shown in Fig. 6. These pipes are staggered in the drawings in Fig. 3 so that air passing through is compelled to be broken up and averted thereby coming in contact with a great amount of surface in the manner shown in Fig. 3. These pipes are made of stamping and wherever edges come together as shown in Fig. 6 at a, a', the edges are welded by either blow pipe or electricity. In Fig. 2 and in Fig. 5 these pipes are shown, Fig. 5 being on an enlarged scale of Fig. 2. These pipes at their upper

and lower ends communicate with water chambers B^3 , B^4 , of course with water tight connections. The lower water chamber B^4 also communicates with the water space between the two shells of the front of the radiator. The water chamber B^3 does not communicate with said space except by an indirect means as shown in Fig. 2 in which B^5 is a direct communicating pipe and B^6 an indirect communicating pipe from the pipe B^5 to the water chamber B^3 . This is controlled also from the aviator's seat by a valve of the usual form B^1 , so that to a certain extent the full circulation of water may be impeded or divided if necessary or deemed desirable by the by-pass control. In Fig. 4 this is shown at the top of the figure. Some of the central tubes B^1 , B^1 extend to the opening B and communicate with a water space between two shells so that the circulation in the tubes is somewhat indirect. I have shown this circulation by arrows. In this sense the circulation of the central set of tubes is somewhat irregular. The water chamber around the opening B only extends to the rear shells of the front so that the water space in that front shell construction does not communicate with the water space around the opening B . The cylinders in a twelve cylinder engine are universally set at an angle so that the cylinders work upon a common shaft. This is well understood. Between the cylinders I have placed a tube C as shown in Fig. 7 with angular openings C' , C' . This is shown somewhat in section in Fig. 7. Air passing through the opening A^6 and between the tubes B^1 , B^1 as shown in Fig. 3 will be caught by a flaring end of the tube C^2 and be forced through the tube C and discharged against some or all of the cylinders through the side opening C' . It will be seen that this flow of air upon the cylinders can be regulated by the damper A^7 .

My radiator is made of sheet metal having its joints welded, this metal being treated to prevent rust. The construction makes a strong radiator which is not liable to be ruptured by sudden stoppages of water. The water chambers are so shaped as to give elasticity to the walls. The cooling and radiating effects can thus be controlled.

The shape of the tubes and surfaces tends to prevent damage from freezing as the expansion thus caused can be taken up by the spring of the metal. The arrangement of the tubes affords a baffling means to the turbulent air passing between them and compels it to deviate repeatedly from a straight line course by its impinging upon the various curved surfaces that it meets in its tortuous course. It will be noted that the arrangement is such upon the respective sides that the air is deflected toward the

center from each side as it emerges from the tubes. This tends to conduct it as shown by the arrows in Fig. 7 into the mouth C^2 of the tube C wherein it is deflected to louvers or other side tubes onto the engine cylinders M heretofore described. I do not intend to limit myself to special tubes as shown in the drawings by which the air may be deflected onto the engine cylinders but any means of deflection such as louvers may be employed. Other forms might be given this tube C as it might be made conical or the tubes or louvers could be enlarged toward the rear end of the engine. The mode of operation is obvious from the foregoing description, and it is also obvious that the opening and closing of the control can be duplicated and only part of the radiator opened and closed to suit conditions of flight or temperature, and perhaps to change head temperature. It is also obvious that the opening B may be circular instead of square as shown in the drawing, or it may be of any other convenient form, it being intended that the opening B shall be surrounded by a water jacket whatever may be its form, as also that the form of nose or head may be of any design or shaped so as best to serve its purpose.

What I claim is:

1. In a radiator, the combination of a double outer shell, a space adapted to be filled with cooling liquid between the walls thereof, said double outer shell having perforations therethrough for the passage of air, said space being adapted to communicate with the water jacket of an engine by means of tanks, a series of crescent shaped pipes connecting the said tanks and so arranged as to form tortuous air passages therethrough and coöperating with the air passages through the double shell.

2. In a radiator, the combination of a double walled outer shell, a space adapted to be filled with cooling liquid between the walls thereof, said outer shell having perforations therethrough for the passage of air, said space being adapted to communicate with the water jacket of an engine, a series of crescent-shaped pipes connecting with said tanks and so arranged as to form tortuous passages therethrough and coöperating with the air passages through the shell, said shell communicating with the upper tank by an alternative passage, a valve in said passage, and means controlling said valve whereby the circulation of the cooling fluid can be varied.

3. In a radiator, the combination of a double walled outer shell, a space adapted to be filled with cooling liquid between the walls thereof, said double outer shell having perforations therethrough for the passage of air, said space being adapted to communicate

cate with the water jacket of an engine, a series of crescent shaped pipes connecting said tanks so arranged as to form tortuous passages therethrough and coöperating with the air passages through the shell, a series of shutters located back of said shell and between it and the aforesaid crescent

shaped tubes, and means controlling said shutters whereby the amount of air passing through the radiator can be varied. 10

In testimony whereof, I sign this specification.

EDWARD T. CURRAN.
